UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

REGENERATIVE HEATING APPARATUS.

Application filed January 6, 1922. Serial No. 527,387.

This invention comprehends improvements in regenerative heating apparatus generally and relates particularly to apparatus that is especially adapted for distilling carbonaceous materials; the invention has for an object the provision of a construction that is highly efficient in operation and which will produce high grade coke, when employed for distilling coal, and effect a substantially complete by-product recovery, although the entire distilling operation is conducted with great conservation of heat.

Important characteristics of the invention are: the provision of a system of combustion in the flame or combustion flues of the heating walls of the distilling chambers, by which system flame or combustion is maintained concurrently in all of the flues of each heating wall, with periodic reversal in direction of flow of the heating gases and the attainment of efficient combustion and heating effects in each direction of flow of the heating gases; the combination of this improved system of combustion with a complete reversible regenerative system for conserving the heat from the combustion flues and imparting such heat to the medium fed into such flues, the regenerative system being constructed and arranged with respect to the flues in such manner as to attain great efficiency in heat conservation and equality in distribution of the heating effect in the several distilling chambers of the battery; a ready adaptability for operation with an extraneously derived gas such as producer gas or blast-furnace gas, for fuel, with a resulting conservation of the entire product of the relatively richer gas of distillation evolved from the distillation of the material, such as coal, in the chambers; and, as a further characteristic combinable with the above mentioned improvements, the attainment of a structure of great strength for withstanding expansive and contractive forces.

In addition to the general objects recited above, the invention has for further objects such other improvements or advantages in construction and operation as are found to obtain in the structures and devices herein-after described or claimed.

In the accompanying drawings forming a part of this specification and showing, for purposes of exemplification, a preferred

form and manner in which the invention may be embodied and practiced, but without limiting the claimed invention specifically to such illustrative instance or instances:

Figure 1 is a composite vertical sectional elevation of a vertical retort construction embodying features above specified and constructed in accordance with the improvements of the present invention, the view being taken in the several vertical planes indicated by the lines A—A, B—B and C—C of Fig. 2;

Fig. 1 is a front elevation of a portion of the battery;

Fig. 2 is a composite vertical sectional elevation of the retort construction taken in the planes indicated by the lines D—D and E—E of Fig. 1; and

Fig. 3 is a composite horizontal sectional elevation, the sectional portions of the figure being taken in the different horizontal planes indicated by the lines F—F, G—G and H—H of Fig. 2.

Fig. 4 is a vertical section on the line J—J of Fig. 3.

The same characters of reference designate the same parts in each of the several views of the drawings.

In its present embodiment, the invention is incorporated in a vertical retort construction for producing metallurgical coke and that is especially designed for the employment of an extraneously derived gas, such as producer gas, for fuel. For convenience, the present description will be confined to this embodiment of the invention; features of construction and operation are, however, capable of other valuable applications, for example, to apparatus generally useful in the heat treatment of materials, or to constructions employing as fuel the distillate gas derived from the distilling chambers, or to constructions embodying the combination principle exemplified in my co-pending application for Letters Patent of the United States for vertical retort battery, filed February 4, 1921; Serial No. 442,357; consequently the invention is not confined in its scope to the specific use and embodiment herein described as an illustrative example.

Referring to the drawings: there are illustrated views of a vertical retort battery of the by-product type, as hereinbefore mentioned. The vertical retort battery embodies

in its construction two series of distilling chambers, such as the series 11 and 12 of vertically elongated retorts or coking chambers, the retorts of each series being contiguous to intermediate heating walls arranged in two series 13 and 14 corresponding to the respective series of retorts 11, 12. The heating walls and the retort chambers extend to a great height as compared with their respective widths and the other crosswise dimensions of the retort battery, and the two series of retorts with their corresponding intermediate heating walls are, according to the present embodiment of the invention, respectively arranged and extend along the opposite sides of the central longitudinal vertical plane of the battery assembly, so as to provide an enclosed space intermediate the opposite sides of the battery for the regenerators, as will hereinafter appear. The heating walls 13, 14 form the side walls of the respective retorts 11, 12, as shown, and the outer ends of the respective retorts, as well as the heating walls are reinforced by side refractory walls designated generally by the reference characters 15. Between the oppositely facing inner ends of the series of retorts 11, 12 and heating walls 13, 14 is located a mediate chamber and wall structure 16 employed for the regenerators and other parts hereinafter described.

As shown in Fig. 3, the retorts of the two series 11 and 12 may be respectively grouped into pairs K and L and the heating walls of the series 13 and 14 may be arranged in groups M and N of three heating walls, corresponding to the pairs of retorts K and L of the series 11 and 12. This arrangement permits the location of a relatively thick transverse wall 17 between each pair of retorts and its corresponding group of heating walls, with the result that ample space is provided for handling of the material carbonized in the retorts of the battery.

The coal to be coked is contained in coal hoppers 18, 19 corresponding to the series 11, 12 of retorts, and supported by the superstructure 20 of the retort battery. These coal hoppers discharge into coal chutes 21 and 22, the lower ends of which communicate with charging holes 23, 24 in the upper ends of the retorts of the series 11, 12. The discharge of coal from the several hoppers may be controlled by manually-operated combined gate and regulating valves 25 individual to the respective chutes 21, 22 and interposed between said chutes and the hoppers 18, 19 above them. The finished coke is discharged through discharge openings 26 at the bottom of the retorts 11, 12. In order to facilitate discharge of the coke from said retorts, the side walls of the latter diverge toward the bottom, as shown more particularly in Fig. 1. Because of the great height of the retorts as compared with their width

and crosswise dimension, the retort battery is preferably employed as a continuous vertical retort. When so employed, a continuous feed of material is maintained through the retorts 11 and 12, with continuous discharge of the finished coke from the bottoms of said retorts into discharge chutes 27 individual to the retorts 11, 12. In the upper portion of the chutes 27, the coke is quenched by water supplied from the water pipe 28 and pipe connections 29 individual to the several chutes 27, the steam produced from the quenching operation being allowed to pass upwardly through the open discharge outlets 26 at the bottoms of the retorts 11, 12 and through the mass of forming coke in said retorts. The introduction of this steam into the retorts permits the continuous maintenance of a water gas reaction in the forming coke, with the result that the gas yield from the retorts 11, 12 is improved. In discharging through the chutes 27, the coke is guided by pivoted aprons 30 into the path of rotary dischargers 31 which insure substantially continuous movement of the finished coke through the chutes 27. From the bottoms of the chutes 27, the coke may be discharged at will through manually-controlled gates 32 on to inclined coke wharves 33, there being an inclined wharf corresponding to each series of retorts 11 and 12. The wharves 33 converge downwardly, as shown in Fig. 2, toward an intermediate coke conveyer 34 and the discharge from the wharves 33 on to the conveyer 34 may be controlled by the individual pivoted gates 35 operated by slides 36.

The heat for coking the charges of coal in the several retorts 11, 12 is derived from the heating walls 13, 14 corresponding to said retorts. Each heating wall 13, 14 is constituted of a plurality of vertical combustion flues 37 that are operatively disposed into single groups in their respective heating walls. That is to say, all of the heating flues of each heating wall operate concurrently for flow in the same direction; in fact, the flow is in the same direction during a reversal period throughout the entire system of flues of the battery.

The regenerators 38 are incorporated in the before mentioned internal structure 16. As shown in Fig. 3, the several regenerators of the battery are structurally disposed in a single series, with walls 39 of substantially equal width between every contiguous pair of regenerators throughout the entire series. Operatively, however, the regenerators are disposed in two groups R and S, each group comprising pairs of adjacent regenerators which alternate with pairs of the other group. When the pairs of regenerators constituting the group R are operating for inflow, that is to say for delivering preheated media to the flues of the heating walls, the

pairs of regenerators of the other group S are operating, for outflow to extract heat from the waste gases discharged from the flues. On reversal of the battery, at the end of an operating period determined by practice, the inflow regenerators become outflow regenerators and the outflow regenerators become inflow regenerators. Each regenerator 38 is preferably a high narrow upright chamber containing open brick-work, commonly called checkerwork and indicated at 39, with a sole channel 40 underneath such checkerwork, the channels forming the soles of such chambers and opening up into the checkerwork. The several regenerators are heated, by the hot combustion products that are exhausted from the flame or combustion flues hereinbefore mentioned and then, upon reversal, impart such heat to the medium that they feed into these flame flues.

In the operation of the battery, the several pairs of regenerators constituting the group R, when in inflow operation, deliver air and fuel gas to the flame flues during the period when the latter are operating for upflow combustion; these regenerators receive the exhaust gases from the flame flues after reversal, that is to say, during the period when the flame flues are operating for downflow combustion. On the other hand, the pairs of regenerators constituting the group S operate for inflow of air and fuel gas to deliver the same to the flues when the latter are operating for downflow combustion, and the said regenerators S operate for outflow to receive the exhaust gases from the flues during the period when the latter are operating for upflow combustion. This method of operation requires the regenerators R to be connected with the lower ends of the flame flues 37 and the regenerators S to be connected with the upper ends of said flame flues. The several pairs of regenerators of each group R and S are constituted of air regenerators A and gas regenerators P, when operating for inflow, and both regenerators of the pairs of each group are constituted of waste gas regenerators W, when operating for outflow. However, the several regenerators R operate for inflow while at the same time the several regenerators S operate for outflow and, on reversal of the flow through the flame flues, the several regenerators S are switched to the inflow function while concurrently the several regenerators R are switched to the outflow function.

As shown, the several regenerators A of the group R communicate at their upper ends by ports 41 with horizontal feed channels 42, the latter leading to vertical feed channels 43 which communicate, at their lower ends, with horizontal channels 44. The said horizontal channels 44 extend be-

neth the groups of flues 37 of both series 13, 14 of heating walls and are connected with the individual flues by ports 45. As shown in Fig. 3, the upper horizontal channels 42 of several regenerators A may be interconnected, such interconnection promoting equality in distribution of the flow through the regenerators and flame flues. The regenerators P of the groups R also communicate by ports 46 with horizontal channels 47 leading to vertical channels 48 that are connected at their lower ends with horizontal channels 49 also extended beneath the flame flues 37 of both series 13, 14 and communicably connected with individual flues by ports 50.

The regenerators A of the group S are communicably connected at their upper ends by ports 51 with horizontal channels 52, there being a pair of such horizontal channels connected at each end of each regenerator, whereby each such regenerator A may have flow connections with the upper ends of the flues of pairs of adjacent heating walls located on the opposite sides of the longitudinal central plane of the battery. The horizontal channels 52 connect with the individual flues through ports 53. The regenerators P of the group S are also communicably connected by ports 54 with pairs of horizontal channels 55 leading on both sides of the longitudinal central plane of the battery to the pairs of heating walls on the opposite sides of said longitudinal plane and connected with the individual flues of said heating walls by means of ducts 56. With this construction, the regenerators P and A of the group S have flow connections with the upper ends of all of the individual flues of the reftort battery.

Extending longitudinally of the battery is a waste gas tunnel 57, said waste gas tunnel leading to the usual waste gas stack. Flow boxes 58 connect the sole channels of the several regenerators individually with the waste gas tunnel 57. The flow boxes 58 are provided with valves 59 for controlling the flow between the individual regenerators and the waste gas tunnel 57. The valves 59 of all of the regenerators of the group S are open, while concurrently the valves 59 of all of the regenerators of the group R are closed. On reversal of the battery the valves 59 of the group R of regenerators are open and the corresponding valves of the group S are closed. Each regenerator A of both groups R and S is provided with a lid 60 which when opened permits air to flow into the regenerator. The series of air lids 60 of the regenerators of the groups R and S are opened in alternation, whereby all the regenerators A of the group R operate concurrently for inflow of air during one reversal period and thereafter, during the next reversal period the regenerators A of the

group S operate for inflow of air, while the regenerators A of the group R are operating for outflow of the waste gases.

A fuel gas main 61 extends longitudinally 5 of the battery and is provided with individual valve connections 62 to the several regenerators P of both groups R and S. In the operation of the battery the valve connections of the regenerators P of the group R 10 are operated in unison to permit the flow of fuel gas into said regenerators from the main 61, while the valve connections 62 of the regenerators P of the group S are closed to shut off the supply of fuel gas. On reversal of the battery the valve connections 15 62 are operated to permit the supply of gas into the regenerators P of the group S and concurrently to cut off the supply of gas from the regenerators P of the group R.

The operation of the retort battery, assuming that a relatively lean or dilute gas, such as ordinary producer gas is employed as the fuel in the heating walls is as follows: If the several regenerators comprising the 20 group R be operating for inflow, and the flues throughout the battery be operating for upflow, it follows that during this period of operation the regenerators P of the group R are employed for preheating the fuel gas which is subsequently introduced into the 25 flues. The regenerators A are employed for preheating the air to support the combustion of the gas in the flues. Concurrently, all the regenerators of the group S operate 30 for outflow. The air and fuel gas passes upwardly through the regenerators A and P of the group R, thence into the horizontal channels 42 and 46, thence downwardly through the vertical channels 43 and 48 into 35 the horizontal channels 44 and 49, from which the air and fuel gas pass through the ports 45 and 50 into the flues 37 of both series 13, 14 of heating walls. The waste gases from the flues exhaust through the top 40 horizontal channels 52 and 55 into the several regenerators of the group S and pass downwardly through the regenerators S and through the open flow boxes 58 of such regenerators into the waste gas tunnel 57. On 45 reversal of the battery, the regenerators A and P of the group S deliver the air and fuel gas through the pairs of channels 52 and 55 into the tops of the several flame flues 37 and the waste gases from said flues exhaust 50 from the bottom thereof into the channels 44, 49, 43 and 48 and thence through the horizontal channels 42 and 47 into the tops of the regenerators of the group R. Flowing downwardly through said regenerators, the 55 waste gases ultimately pass through their open flow boxes 58 into the waste gas tunnel 57.

The by-products and distillate gases from the several retorts or coking chambers of 60 both series 11, 12 pass out of the tops of the

said retorts through ascension pipes 64, 65 individual to the respective retorts of the series 11, 12. These ascension pipes carry the distillate and by-products to a common 70 collecting main 66, through which the distillate and by-products may pass to the usual by-product recovery apparatus. In the construction of the battery, the expansion joints, such as the joints 63, may be located in vertical planes and remotely from the 75 heating walls, with the result that leakages or short circuiting of the flow of the various media are avoided.

As shown more especially in Figs. 2 and 3 of the drawings, the regenerators, which 80 extend from top to bottom of the structure and having their horizontal levels coinciding with similar horizontal levels of the alternating retorts or coking chambers and heating walls, are disposed in a longitudinal row 85 located in the interior of the battery structure, whereas the alternate retorts and heating walls are located in longitudinal rows at the opposite sides of the battery structure. This arrangement is productive of important 90 advantages in practice, among which may be mentioned the fact that the outside ends of the retorts and heating walls coincide, according to the present embodiment of the invention with the opposite side walls of 95 the battery structure, thereby rendering the heating walls and retorts directly accessible from such longitudinal side walls for regulatory, repair, and other purposes.

The invention as hereinabove set forth 100 may be variously embodied within the scope of the claims hereinafter made.

I claim:

1. In a vertical retort battery, in combination: a plurality of high narrow retort chambers, each receiving through its top the charge to be coked and discharging through its bottom the coked charge; heating walls alternating with the retort chambers and respectively constituted of vertical combustion flues operable in unison for upflow and downflow combustion in alternation; two groups of high narrow regenerators disposed at the same level in a different region of the battery from the heating walls, one 105 group operating for inflow during upflow combustion of the flues and the other group operating for inflow during the alternate downflow combustion of the flues, each group of said regenerators comprising air 110 and fuel gas regenerators; and flow connections between the first mentioned group of regenerators and the bottoms of the flues, and flow connections between the second mentioned group of regenerators and the 115 tops of the flues; substantially as specified.

2. In a vertical retort battery, in combination: a plurality of high narrow retort chambers, each receiving through its top the charge to be coked and discharging

- through its bottom the coked charge; heating walls alternating with the retort chambers and respectively constituted of vertical combustion flues operable in unison for upflow and downflow combustion in alternation; two groups of high narrow regenerators disposed at the same level in a different region of the battery from the heating walls, one group operating for inflow during upflow combustion of the flues and the other group operating for inflow during the alternate downflow combustion of the flues; and flow connections between the first mentioned group of regenerators and the bottoms of the flues, and flow connections between the second mentioned group of regenerators and the tops of the flues; substantially as specified.
5. In a vertical retort battery, in combination: a plurality of high narrow retort chambers, each receiving through its top the charge to be coked and discharging through its bottom the coked charge; heating walls alternating with the retort chambers and respectively constituted of vertical combustion flues operable in unison for upflow and downflow combustion in alternation; and two groups of high narrow regenerators disposed at the same level in a different region of the battery from the heating walls, one group being connected with the bottom of the flues; and the other group being connected with the tops of the flues; substantially as specified.
6. In a vertical retort battery, in combination: two series of high narrow retort chambers respectively disposed along the opposite sides of the battery, each chamber receiving through its top the charge to be coked and discharging through its bottom the coked charge; heating walls contiguous to such retort chambers and respectively constituted of combustion flues alternately operable in unison for either an upflow or downflow combustion. two groups of high narrow regenerators disposed in the interior of the battery between the two series of retort chambers, one operating for inflow during upflow combustion of the flues and the other group operating for inflow during the alternate downflow combustion of the flues, each group of said regenerators comprising air and fuel gas regenerators; and flow connections between the first mentioned group of regenerators and the bottoms of the flues, and flow connections between the second mentioned group of regenerators and the tops of the flues; substantially as specified.
7. In a vertical retort battery, in combination: two series of high narrow retort chambers respectively disposed along the opposite sides of the battery, each chamber receiving through its top the charge to be coked and discharging through its bottom the coked charge; heating walls contiguous to such retort chambers and respectively constituted of combustion flues alternately operable in unison for either an upflow or downflow combustion; two groups of high narrow regenerators disposed in the interior of the battery between the two series of retort chambers, one operating for inflow during upflow combustion of the flues and the other group operating for inflow during the alternate downflow combustion of the flues. and flow connections between the first mentioned group of regenerators and the bottoms of the flues, and flow connections between the second mentioned group of regenerators and the tops of the flues; substantially as specified.
8. In a vertical retort battery, in combination: two series of retort chambers respectively disposed along the opposite sides of the battery, each chamber receiving through its top the charge to be coked and discharging through its bottom the coked charge; heating walls contiguous to such retort chambers and respectively constituted of combustion flues alternately operable in unison for either an upflow or downflow com-
- 10 15 20 25 30 35 40 45 50 55 60 65 70 75 80 85 90 95 100 105 110 115 120 125 130

bustion; two groups of regenerators disposed in the interior of the battery between the two series of retort chambers, one operating for inflow during upflow combustion 5 of the flues and the other group operating for inflow during the alternate downflow combustion of the flues; and flow connections between the first mentioned group of regenerators and the bottoms of the flues, 10 and flow connections between the second mentioned group of regenerators and the tops of the flues; substantially as specified.

9. A battery structure for distilling carbonaceous materials having high narrow distilling chambers attenuated in horizontal section and flued heating walls alternating with said distilling chambers, the walls and chambers being disposed in series along the opposite sides of the battery structure, combined with high narrow regenerators disposed in the interior of the structure and between the opposite series of said distilling chambers and heating walls; substantially as specified.

25. 10. A battery structure for distilling carbonaceous materials having distilling chambers attenuated in horizontal section and flued heating walls contiguous to said distilling chambers, the walls and chambers being disposed in series along the opposite sides of the battery structure, combined with regenerators disposed in the interior of the structure and between the opposite series of said distilling chambers and heating walls; substantially as specified.

11. A vertical retort battery having series of retort chambers attenuated in horizontal section and contiguous flued heating walls disposed along the opposite sides of the battery structure, combined with two groups of regenerators disposed in the interior of the battery structure between the two series of such retorts and the heating walls, one group of said regenerators being communicably connected with the bottoms of the heating walls and the other group of said regenerators being communicably connected with the tops of the heating walls; substantially as specified.

50. 12. A vertical retort battery having retort chambers attenuated in horizontal section, heating walls constituted of vertical combustion flues each operable alternately for combustion in opposite directions, combined with regenerators disposed into groups alternating respectively with each other and communicably connected with said combustion flues, the alternate groups being adapted to operate as inflow groups when the intermediate groups operate as outflow groups and vice versa; substantially as specified.

55. 13. A vertical retort battery having retort chambers attenuated in horizontal section, heating walls constituted of vertical combustion flues each operable alternately for

combustion in opposite directions, combined with regenerators disposed into groups alternating respectively with each other and communicably connected with said combustion flues, the alternate groups being adapted to operate as inflow groups when the intermediate groups operate as outflow groups and vice versa, the regenerators when operating for inflow comprising both air and fuel gas regenerators; substantially as specified.

14. A vertical retort battery having retort chambers attenuated in horizontal section and contiguous vertically flued heating walls disposed along its opposite sides, combined with regenerators disposed in the interior of the battery structure between the opposite series of said retorts and heating walls, the said regenerators when operating for inflow comprising both air and fuel gas regenerators; substantially as specified.

15. A vertical retort battery having retort chambers attenuated in horizontal section and contiguous vertically flued heating walls, disposed along its opposite sides, combined with regenerators disposed in the interior of the battery structure between the opposite series of said retorts and heating walls; substantially as specified.

16. A battery structure for effecting treatment of materials with extraneously-developed heat, having vertically-heated walls contiguous to the space in which the material is treated, combined with regenerators located in a different region of the battery from the heating walls and at substantially the same level and disposed into groups alternating respectively with each other, said regenerators being communicably connected with the said vertically-heated walls, the alternate groups being adapted to operate as inflow groups when the intermediate groups operate as outflow groups and vice versa, substantially as specified.

17. A regenerative retort oven battery having a row of vertical retorts alternating with vertically flued heating walls, the flues of each heating wall being all operative concurrently in the same direction, combined with a series of regenerators all located in a single row parallel to at least one row of retorts and heating walls.

18. A regenerative retort oven battery having a row of vertical retorts alternating with vertically flued heating walls, the flues of each heating wall being all operative concurrently in the same direction, combined with a series of regenerators all located in a single row parallel to at least one row of retorts and heating walls, the regenerators being arranged in groups of which the alternate groups are connected at the tops of the flues and the other groups with the bottoms of the flues.

19. A regenerative retort oven battery

- having a row of vertical retorts alternating with vertically flued heating walls, the flues of each heating wall being all operative concurrently in the same direction, combined 5 with a series of regenerators all located in a single row parallel to at least one row of retorts and heating walls, the regenerators being arranged in groups of which the alternate groups operate for inflow while the other groups operate for outflow.
20. In a vertical retort battery in combination: retort chambers; heating walls provided with flues having their respective ends at different levels; regenerators connected by ducts with the tops of the flues, and other regenerators on the same level connected by ducts with the bottoms of the flues; and horizontal channels disposed at different levels for connecting the tops of the regenerators of different groups with said ducts.
21. A regenerative vertical oven battery having two opposite rows of vertical ovens alternating with flued heating walls, combined with a longitudinal row of regenerators located between the aforesaid rows of ovens and heating walls, whereby at least one wall of each oven and at least one end of each heating wall is accessible from a side wall of the battery structure; substantially as specified.
22. A regenerative vertical oven battery having two opposite rows of vertical ovens alternating with flued heating walls, combined with a longitudinal row of regenerators located between the aforesaid rows of ovens and heating walls, whereby at least one wall of each oven and at least one end of each heating wall is accessible from a side wall of the battery structure, certain of said regenerators being adapted to operate as inflow when others of said regenerators operate for outflow and vice versa; substantially as specified.
23. A regenerative vertical oven battery having a row of vertical ovens alternating with flued heating walls, in which at least one wall of each oven and at least one end of each heating wall is located at a side wall of the battery structure, combined with a row of regenerators communicably connected with said heating walls and disposed so that the major vertical extent of the regenerators intersects horizontal levels of the heating walls and alternate ovens; substantially as specified.
24. A battery structure for distilling carbonaceous materials having distilling chambers and flued heating walls contiguous thereto, the walls and chambers being dis-
- posed in series along the opposite sides of the battery structure, combined with regenerators disposed in the interior of the structure between the opposite series of said distilling chambers and heating walls, the respective regenerators being connected in common to the heating walls of the two series; substantially as specified.
25. A vertical retort battery structure comprising in combination: coking chambers; flued heating walls contiguous thereto; and regenerators on one side of and on substantially the same level as said coking chambers and flued heating walls and communicably connected to the latter, said structure being provided with an expansion joint extending into a regenerator chamber.
26. A vertical retort battery structure comprising in combination: coking chambers; flued heating walls contiguous thereto; and regenerators on one side of said coking chambers and flued heating walls and communicably connected to the latter, said structure being provided with an expansion joint extending from the ends of a regenerator chamber to the opposite sides of the battery.
27. A vertical retort battery structure comprising in combination: coking chambers; flued heating walls contiguous thereto; and regenerators on one side of said coking chambers and flued heating walls and communicably connected to the latter, said structure being provided with an expansion joint separating certain of the regenerators from each other.
28. A vertical retort battery structure for distilling carbonaceous material having distilling chambers and flued heating walls alternating therewith arranged in sets on opposite sides of the battery respectively; and regenerators disposed between the opposite sets of said distilling chambers and heating walls, said structure being provided intermediate its ends with a transverse expansion joint extending crosswise of the battery and into a regenerator chamber.
29. A vertical retort battery structure for distilling carbonaceous material having distilling chambers and flued heating walls alternating therewith arranged in sets on opposite sides of the battery respectively; and regenerators disposed between the opposite sets of said distilling chambers and heating walls, said structure being provided intermediate its ends with a transverse expansion joint extending crosswise of the battery.

In testimony whereof I have hereunto set my hand.

JOSEPH VAN ACKEREN.
